NICHOLAS B. HADLEY, OF PROVIDENCE, RHODE ISLAND.

Letters Patent No. 91,117, dated June 8, 1869.

IMPROVEMENT IN MACHINES FOR THREADING SCREWS.

The Schedule referred to in these Letters Patent and making part of the same.

To all whom it may concern:

Be it known that I, NICHOLAS B. HADLEY, of the city and county of Providence, in the State of Rhode Island, have invented certain new and useful Improvements in Machines for Threading Screws; and I do hereby declare that the following is a full and exact description thereof.

My invention is intended for threading small metallic screws, sometimes denominated screw-nails, receiving the blanks previously prepared by other machinery or by hand.

My machine is necessarily complicated, but as many of the parts are similar to those heretofore in use, I will describe only the novel parts, with so much of the ordinary parts as is necessary to understand their relations thereto.

My improvements relate to the cutting of screws having more than one thread. I prefer the form of thread described in the patent issued to Samuel Pratt, dated October 25, 1853. I prefer to make the screws with three threads.

My machine provides for cutting the several threads separately, by repeating the operation of bringing up the cutter and traversing it along the screw.

My machine cuts all the grooves slightly at first, and afterwards deepens them.

The accompanying drawings form a part of this specification.

Figure 1 is a front view, showing the novel parts of the machine.

Figure 2 is a plan view.

Figure 3 is a cross-section through the novel parts, on line S S in fig. 2.

Figure 4 is a horizontal section, showing more clearly the wedges which draw the tool rigidly and accurately to its work.

Figure 5 is a plan view, merely illustrating the mode of feeding forward the cutting-tool at each cut. This is not claimed as my invention.

Figure 6 is a vertical section, showing the same.

Similar letters of reference indicate like parts in all the figures.

Tints are employed merely to aid in distinguishing parts, and do not imply difference of material. The materials may be iron or steel.

A is a rigid frame-work, which may be of cast-iron, which supports the several novel parts, as also the many ordinary parts not represented.

B is an arbor, provided with suitable mechanism, not represented, for seizing and releasing a screw-blank, indicated in red outline at m. It is supported in bearings in the frame A, as represented, and is turned by a steam-engine or other power, not represented, in the direction indicated by the arrow.

It is enclosed by the bushing C, one end of which is enlarged, and forms a friction-pulley, as indicated

by C'. The motion which actuates the cutting-tool is transmitted through this bushing C.

Within the pulley is mounted a lever-catch, D, turning on a centre, d, which is carried in the pulley C', and consequently rotates with the bushing C.

The arbor B is provided with three rectangular notches within the friction-pulley C', as indicated by b¹ b² b³.

One end of the lever-catch D is adapted to drop into and hold these notches, successively, one after the other, the other end of the lever-catch D projecting through a slot in the exterior of the friction-pulley C', with liberty to turn a little on the centre, d.

There is a spring, E, carried within the friction-pulley C', which tends to hold the lever-catch D always fast in one of the notches b¹, b², or b³.

When, by contact with any suitable object, the lever-catch D is tilted out of its hold in such notch, the arbor B is free to turn a portion of the revolution without giving a corresponding motion to the bushing C and its connections.

It is by this means that I change the position of the screw-blank, relatively to the threading-tool, at short intervals, so as to cut three threads thereon.

It will be understood that the tool, and the means for moving it longitudinally of the screw, are of the ordinary character, and may be operated by the aid of another shaft, mounted in a convenient position, and provided with the usual appliances.

Figs. 5 and 6 illustrate this, and will be briefly described.

T is the tool, T' the tool-post or lever, and t a shaft turning therein, and holding the tool-post between collars, not represented.

This shaft is threaded at one portion of its length, and is free to move endwise, carrying the tool-post and tool with it.

The frame H forces the tool back to cut, through the medium of the back-rest h¹, which presses against it.

H² is a frame for bringing the back-rest into line with the screw to be cut.

This turns upon pin H³, in frame H.

There are set-screws, H⁴ and H⁵, in frame H, to regulate the back-rest.

The frame H, in moving back, forces the back-rest h¹ in contact with tool-post T', thereby forcing the tool T upon the screw M, to be cut.

As the tool reaches the part where the point should commence to taper off, the tool-post T' comes in contact with conical collar h², which forces the tool T back further, thereby forming the point.

The forward motion of the frame H, and its connections, then allows the tool T to move away from the screw M, for the return movement.

At this period one of the recesses in cam u comes opposite the end of lever U', into which recess it falls,

thus liberating the half nut U from the screw on the shaft of tool-post T, and the latter is carried rapidly back to the place of beginning, by means of a spring, not represented.

The collar h² is made to adjust, by sliding on the back-rest h¹, to suit length of screw, being fixed in the required position by a set-screw, h³.

The tilting of the lever-catch D at the proper period is effected by means of the sliding-piece F, which is supported on ways F', with liberty to slide.

There is a spiral spring, f, which tends to hold this slide always out of use, but the latter is thrown into position, to act on the lever-catch D at intervals, by mechanism which will be explained below.

The slide F is so formed, that when it is moved into position, to tilt the lever-catch D, it may press gently against the exterior of the friction-pulley C', and retard its motion, so as to insure the permanent disengagement of the catch from the arbor.

In other words, the tilting of the lever-catch D, to disengage it from the notches, is only for a very brief period, but it is sufficient to allow the arbor to get so much ahead of the bushing that when the lever-catch D is again released it will not drop into the same notch, but will remain while the arbor B performs a third of a revolution, and will then catch into the next succeeding notch, after which the work will proceed as before, excepting that the screw-blank will be held in a different position, and the cutter or tool which cuts the metal will act on it in a different spiral path, so as to form a separate groove or thread.

The friction of the piece F against the exterior of the friction-pulley C', tends to increase the certainty that the lever-catch D will not, on being released, drop back into the same notch from which it has just been lifted.

The gear-wheel C², on the bushing C, acts, through the gearing C³ C⁴ C⁵, to give a correspondingly nearly-continuous motion, but at a much-reduced speed, to the back shaft G, which is supported in bearings in the frame A, as represented, and turns in the direction indicated by the arrow.

G¹ G² are wipers, which give a motion, at intervals, to the slide F, above described; that is to say, the slide F is touched, by the points of the cams G¹ G², at proper intervals, and shifted into position to retard the bushing C, and its connections, a third of a revolution, and is then released.

I have not deemed it necessary to encumber this description with drawings of the cutter or chisel which forms the threads, nor of the ordinary approved mechanism by which it is moved rapidly forward as the screw-blank is turned.

It will be understood that the chisel is modified in form, according to the form of the thread required, and that it is traversed steadily along the screw-blank, in the same manner as in ordinary screw-machines, except that the mechanism is so proportioned and adjusted as to traverse it along faster than in ordinary machines; that is to say, the thread is quicker than in ordinary screws. So, also, the means by which the cutter is moved back, out of contact with the screw-threads, for the back-traverse to resume its place after each cut, and prepare for another one, is very much like that ordinarily employed; but being intimately connected with my peculiar mechanism for bringing the cutter up to its place, to produce the requisite succession of cuts for each thread, I have represented, and will proceed to describe, some of the parts thereof.

The cutter, with parts of the mechanism for traversing it, is carried on the framing H.

It is necessary, therefore, in order to describe all that relates to the bringing up of the cutter to its work, simply to describe the motions of the framing H.

This frame is supported at the front on bearings I¹

I², which may be screws tapped through A, and is adapted to move out and in thereon to the required extent.

The back part of the frame H embraces a system of wedges, acting between it and a portion of the frame-work A'.

At the front of the framing A' is a spring, J, which tends to throw the framing H forward, and there is at the back an adjusting-screw, h, which bears against a broad bearing-piece, H'.

It follows that the wedges or other operating-parts, by acting properly against the bearing-piece H', can control the position of the framing H, and consequently the cutter which forms the threads.

There are two wedges contained within the frame-work A'. These two are differently operated, and are peculiarly adapted to each other, to give the right motion to the framing H.

One large wedge, K, is operated at regular intervals, and to a uniform extent. This wedge provides for the backward motion of the cutter after each traverse. This uniform motion is necessarily always sufficient to liberate the cutter entirely from the thread after the thread is fully cut.

The other wedge, L, is for graduating the depth of the cut, making, first, a slight cut for each thread, and afterwards repeating and deepening, till the full thread is formed.

The large wedge K bears fairly, by its front face, against the adjacent portions of the framing A', and bears fairly, by its back face, against a rectangular bar, L'.

The wedge K receives its regular reciprocating motion from a peculiar cam fixed on the shaft G, and acting on the pin or projection K', which extends backward and downward from the wedge K, as represented.

The cam is peculiarly formed, in two parts, adapted to act on opposite sides of the pin K'.

One part, G³, drives in the wedge, and holds it in steadily during a large part of each revolution; but at the intervals when the cutter is to be moved back, recesses in this part of the cam become effective, and allow the wedge K to slide back.

The wedge K, being nicely fitted and lubricated, tends to slide out, by the force of the spring J and J'; but to insure this motion, I provide the parts G⁴ of the cam, which, acting on the pin or projection K', at the proper moment, compel the latter to enter the recesses in the cam G³.

If the wedge K does not move back promptly, of itself, when liberated by the cam G³, it is compelled to do so by the cam G⁴. This makes a positive motion for this portion of the mechanism.

I will now describe the small wedge L, and its connections with the mechanism for imparting its peculiar motions.

It is fixed on the back of the rectangular bar L', which forms the back bearing for the wedge K, as above intimated.

This bar L' is pressed gently forward by the pins a, actuated by springs a' a''.

The pin l, inserted in the end of the bar L', as represented, is received in slots n, in a rod, N, which rod controls the position endwise, and gives, at proper intervals, a slight end-motion to the bar L', without interfering with the side-motion thereof, received from the wedge K, as above described.

In other words, the rod N constitutes an extension of the bar L', but without the side-motion thereof, the bar N being supported in a fixed bearing on the frame-work A, with liberty simply to move endwise.

This bar N is urged to the right by a spring, not represented, and it is moved to the left by the face-cam acting on a pin, N', as represented.

This cam is formed in steps, O¹ O² O³, correspond-

ing to the depths to which the several cuts are made, in cutting the threads of the screw, and the cam being turned slowly, the width of the several steps is made sufficient to allow of the first three cuts at a certain moderate depth, one cut for each spiral groove. This is while the pin N' rests on the part O^1 of the cam.

After this, the part O^2 of the cam comes into play, pressing the pin N' , and consequently the wedge L , a little further to the left, and holding it there while three more cuts are made, one for each thread of the screw.

After this, the third and finishing-portion of the cam comes into play, and urges the pin N' , and consequently the wedge L , a very little further to the left.

The means by which the peculiar cam, $O^1 O^2$, &c., is slowly rotated, will be readily understood from an inspection of the drawings.

The cams or teeth $G^3 G^4$ act, at intervals, on the wheel P , giving a slow intermittent rotatory motion to this latter, as also to the connected wheel P' .

This latter wheel gears into the larger wheel Q , which latter is fixed on the sleeve R , and thus turns the cam $O^1 O^2$, &c., around intermittently, with a slow motion, exactly adapted to the purposes required.

It will be readily understood that my invention can be employed to make screws with only two threads, instead of three, by employing only two of the notches $b b$, distributed opposite to each other, or to make four, or any other desired number of threads, by employing a corresponding number of notches.

It will be understood, that in such case the steps $O^1 O^2$, &c., in the cam which operates the rod N , are correspondingly increased or diminished in number.

Many modifications may be made in various other parts of the mechanism, without defeating the objects of my invention. Thus, for example, the back shaft

G may be geared so as to revolve twice as rapidly as is here provided, and may, in such case, be correspondingly modified in the cams.

Having now fully described my invention,

What I claim as new, and desire to secure by Letters Patent, is as follows:

1. I claim the combination of the notched arbor B , spring-catch D , pulley C' , tripping-wedge F , tappets $G^1 G^2$, and retracting-spring f , all arranged as and for the purposes set forth.

2. The described arrangement of the tripping-piece F , pulley C' , and spring-catch D , substantially as set forth.

3. I claim the cams $G^5 G^6$, constructed as described, and arranged as shown, upon the shaft G , in combination with the projection K' of wedge K , and the tool-carrier H and spring J , whereby said wedge is moved back and forth, by a positive motion, under all conditions, as set forth.

4. I claim the relative arrangement of the wedge K , wedge-bar $L L'$, bearing-block H' , and tool-carrier H , substantially as herein set forth.

5. The shaft N , in combination with the cams $O^1 O^2 O^3$, wedge-bar $L L'$, and wedge K , the parts $L' N$ being connected by means of a pin working in a slot, whereby said wedge-bar L' is operated, both longitudinally and laterally, and the said motions are rendered independent of each other, substantially as herein described.

In testimony whereof, I have hereunto set my hand, in the presence of two subscribing witnesses.

NICHOLAS B. HADLEY.
